[57] CLAIM

The ornamental design for spout, as shown and described.

DESCRIPTION

FIG. 1 is a perspective view of our new design of a spout; FIG. 2 is a front view of our new design of the spout; FIG. 3 is a rear view of our new design of the spout; FIG. 4 is a right side view of our new design of the spout, a left side view thereof being a mirror image of the right side view;

FIG. 5 is a top view of our new design of the spout; FIG. 6 is a bottom view of our new design of the spout; and, FIG. 7 is a perspective view of our new design of a spout. The flange at the base of the spout and the discharge end of the spout are shown in broken lines for illustrative purposes only and forms no part of the claimed design.
